UNITED STATES PATENT OFFICE.

WELLSLEY H. LAWRENCE, OF WORCESTER, MASSACHUSETTS, ASSIGNOR TO PARKER WIRE GOODS CO., OF WORCESTER, MASSACHUSETTS, A CORPORATION OF MASSACHUSETTS.

FAN GUARD.

Application filed November 27, 1925. Serial No. 71,623.

This invention relates to a fan guard for use on electrical ventilating fans, such guards being commonly made with a plurality of radial or substantially radial wire 5 spokes.

My invention relates particularly to the means provided for securing the inner ends of these spokes in position, and it is the object of my invention to provide an improved 10 construction for this purpose by which the inner ends of the spokes will be very firmly held from displacement, while at the same time the construction is economical to manufacture and is of a pleasing appearance.

15 My invention further relates to certain arrangements and combinations of parts which will be hereinafter described and more particularly pointed out in the appended claims.

The preferred form of the invention is 20 shown in the drawings, in which

Fig. 1 is a partial front view of my improved fan guard;

Fig. 2 is a rear view of the center plate or disc;

25 Fig. 3 is a view similar to Fig. 2 but showing the ends of the spokes assembled and secured in the center plate;

Fig. 4 is a detail sectional view taken along the line 4—4 in Fig. 2;

20 Fig. 5 is a view similar to Fig. 4, but showing the end of a spoke assembled with the center plate;

Fig. 6 is a view similar to Fig. 5 but showing the spoke secured in position; and

35 Figs. 7 and 8 are detail sectional views taken along the lines 7—7 and 8—8 in Fig. 6.

Referring to the drawings, I have shown a portion of a fan guard comprising one or more outer rings 10, a center plate 11 and 40 a plurality of substantially radial spokes 12. The ring 10 and spokes 12 are commonly formed of relatively heavy wire, and the spokes 12 may be given a curved outline for ornamental purposes if desired.

45 The center plate 11 comprises a peripheral edge portion 15 and a center portion 16. A circular series of openings 17 are provided in the center portion 16 and a series of substantially radial depressions 18 extend out-

ward from the opening 17 to the inner edge 50 of the peripheral flange 15.

The spokes 12 are offset at their inner ends, as indicated at 20 in Fig. 5, these ends 20 being adapted to extend through the openings 17 in the center portion 16. After 55 the spokes are thus assembled with the center plate, the ends 20 of the spokes 12 are headed or upset as indicated in Fig. 6, to prevent withdrawal or displacement of the 60 spokes.

At the same time, or by a subsequent operation, the extreme inner part of the depressed portion 18 is swedged toward the center of the plate, as also indicated in Fig. 6, forcing a portion of the metal 23 against 65 the upset end 20 of the spoke and also forcing another portion of metal 24 into the radial portion of the spoke. The end of the spoke 12 is thus very firmly secured in the plate 20, and is held from displacement longitudinally or from angular movement about the upset end 20.

It will be noted that the flange portion 15 is positioned in a plane at the rear of the spokes 12 and that it forms a continuous surface surrounding the depressions 18.

Having thus described my invention and the advantages thereof, I do not wish to be limited to the details herein disclosed, but what I claim is:—

1. In a fan guard, a plurality of substantially radial spokes having offset end portions, and a disc having depressions to receive portions of said spokes and having openings to receive said end portions, said end portions being upset at the rear face of said disc.

2. In a fan guard, a plurality of substantially radial spokes having offset end portions, and a disc having depressions to receive portions of said spokes and having openings to receive said end portions, said end portions being upset at the rear face of said disc, and an inner end portion of the depressed stock of said disc being swedged against said upset end portion of each spoke.

3. In a fan guard, a plurality of substan-

5 tially radial spokes having offset end portions, and a disc having substantially radial depressions to receive said spokes and having openings to receive said end portions, 10 said end portions being upset at the rear face of said disc, and said disc having also a peripheral edge portion extending continuously behind said spokes at the outer ends of said radial depressions.

10 4. In a fan guard, a center plate comprising

15 ing a center portion having a circular series of openings therethrough, and a series of depressions leading outwardly therefrom to the outer edge of said center portion, and said plate having also a continuous peripheral edge portion positioned in a plane rearward of said center portion.

In testimony whereof I have hereunto affixed my signature.

WELLSLEY H. LAWRENCE.
